US0D1056976S

(12) **United States Design Patent** (10) Patent No.: **US D1,056,976 S**
(45) Date of Patent: ** Jan. 7, 2025

(54) **WELDING MACHINE**

(71) Applicant: **DAIHEN CORPORATION**, Osaka (JP)

(72) Inventors: **Hideki Shimogiku**, Osaka (JP); **Tetsuya Eto**, Osaka (JP); **Ryuji Tanaka**, Osaka (JP); **Kohei Ono**, Osaka (JP)

(73) Assignee: **DAIHEN CORPORATION**, Osaka (JP)

(**) Term: **15 Years**

(21) Appl. No.: **29/868,930**

(22) Filed: **Dec. 16, 2022**

(30) **Foreign Application Priority Data**

Jun. 30, 2022 (JP) ..... 2022-014069 D

(51) **LOC (15) Cl.** **15-09**

(52) **U.S. Cl.**

USPC **D15/144**

(57) **CLAIM**

The ornamental design for a welding machine, as shown and described.

DESCRIPTION

FIG. 1 is a front, top and right side perspective view of a welding machine showing our new design;
FIG. 2 is a rear, bottom and left side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof; and,

FIG. 8 is a left side view thereof.

The broken lines illustrate portions of the welding machine that form no part of the claimed design.

1 Claim, 8 Drawing Sheets
